Patented Mar. 23, 1926.

UNITED STATES PATENT OFFICE.

OSCAR G. EDMOND, OF SPOKANE, WASHINGTON, ASSIGNEE OF ONE-HALF TO WHITE
PINE SASH COMPANY, OF SPOKANE, WASHINGTON.

WOODWORKING MACHINE.

Application filed July 25, 1924. Serial No. 728,246.

To all whom it may concern:

Be it known that I, OSCAR G. EDMOND, a citizen of the United States, residing at Spokane, in Spokane County and State of Washington, have invented certain new and useful Improvements in Woodworking Machines, of which the following is a specification.

My present invention relates to improvements in woodworking machines especially adapted for use in assembling and joining rectangular frames such as screen door frames, window sash, and other similar structures utilizing mortise and tenon joints. The primary object of the invention is the provision of a power operated and pedal or manually controlled machine of this character whereby the opposed sides and ends of a rectangular frame may with accuracy and convenience be first placed or assembled in proper position and then quickly compressed or joined to form a true and rigid structure. Two complementary and reciprocating heads and two complementary and reciprocating plates are arranged to reciprocate on diametrical lines for an inward or working movement of the machine and an outward release movement of the machine, and the reciprocation of the parts is accomplished during a single revolution of the power shaft of the machine.

Means are provided for automatically stopping the operation of the machine at the end of each movement or stroke of the reciprocal heads and plates, and an emergency device is also used in connection with the automatic stopping means in case of accident.

The invention consists in certain novel combinations and arrangements of parts as will hereinafter be more fully set forth and claimed.

In the accompanying drawings I have illustrated one complete example of the physical embodiment of my invention wherein the parts are combined and arranged in accordance with the best mode I have thus far devised for the practical application of the principles of my invention.

For convenience in describing and illustrating one exemplification of my invention I have shown in the drawings in Figs. 3, 4 and 7 a window sash, and shall hereinafter refer to the manufacture of such a

sash, but it will be understood that the machine is adapted for use in the manufacture of frames other than window sash.

The window sash to be assembled is indicated in the drawings as having a top rail T and bottom rail B, and side pieces or stiles S and S' all of which are mortised and tenoned in suitable machines for the purpose before being placed in this machine by the operator for joining. In Figures 3 and 4 the sash is provided with interior cross bars A for four panes of glass, while in Figure 7 the sash has inner bars C for six panes of glass. All of these members are mortised and tenoned and ready for joining before being placed in this machine, in the position indicated in Figure 7.

Figure 1 is a top plan view of a machine embodying my invention a rectangular frame being shown therein in dotted lines.

Figure 2 is a front elevation of the machine of Fig. 1.

Figure 3 is a vertical sectional view at line 3—3 of Fig. 1 looking toward the right and showing the side bars of a sash in section.

Figure 4 is a vertical sectional view at line 4—4 Fig. 1 looking toward the left and also showing the sides or stiles of the sash in section.

Figure 5 is an enlarged sectional detail view illustrating one of the reciprocable heads and devices for operating both of the heads for the complementary top and bottom rails of a sash.

Figure 6 is an enlarged detail view of the stop mechanism for the machine.

Figure 7 is a diagrammatic top plan view of the four holders or pairs of heads and plates for the sash, together with intermediate devices for engaging and retaining the interior bars of the sash, the parts being assembled for a window sash with six lights or panes of glass.

Figure 8 is an enlarged detail vertical sectional view of the mechanism for moving the carriers for the intermediate or inner bars of the sash.

Figure 9 is a detail view showing the side rails or plates of the machine and the adjusting devices therefor.

Figures 10 and 11 are perspective views of adjustable blocks for centering and aligning the inner bars of the sash.

The machine has the usual legs or supporting frame 1 and a table top 2, and above the table is arranged the horizontally disposed clamping frame which comprises complementary slide heads 3 and 4 and complementary slide plates 5 and 6, which move on diametrical lines. The top and bottom rails are carried on the reciprocating heads and the side pieces or stiles of the sash are carried on the reciprocating plates. Adjustable stops 5' and 6' are attached to the plates 5 and 6 as gages for use in properly positioning the stiles S and S' on the plates. On the working stroke of the machine the heads and plates move the top and bottom rails and side stiles of the sash into engagement and then clamp these members together by means of their mortise and tenon joints.

The reciprocating movement of the heads 3 and 4 and the plates 5 and 6 is accomplished from the power shaft 7 located below the table top and journaled in suitable bearings in the main frame of the machine.

For actuating the reciprocable slide heads 3 and 4 from the power shaft 7 I employ a pair of cam wheels 8 and 9 fixed by set screws 10 on the shaft and provided with exterior cam grooves 11 as best seen in Fig. 5 of the drawings. Each of these operating cam wheels co-acts with a pin as 12 and 13 fixed to and projecting downwardly from a flanged slide bracket as 14 located beneath the table top and guided on tongues 14' of the table. Each of these slide brackets has an upright lug 15 projecting through the center slot 16 of the table top. These lugs 15 support a pair of oppositely disposed, horizontal, screw bars 17 and 18, which perform the functions of pitmen and are journaled to rotate in the lugs for adjustment of the slide heads 3 and 4 toward or away from each other.

The slide heads 3 and 4 are each fashioned with a traveling nut 19 through which said screw bars 17 and 18 pass, and it will be apparent that by turning the bars with a tool applied at the squared ends 20 of the bars they may be turned in their lugs and nuts to move the heads. The slide heads may thus be moved toward or away from the center of the machine to adapt them for the assemblage of small or larger window sash. The traveling nuts move relatively to the screw bars only when the bars are turned. The nuts are bolted at 19' to the slide heads 3 and 4 and move with the bars and heads when the screw bars perform the functions of pitmen and move on their longitudinal axes by the action of the cam devices to slide the heads 3 and 4.

On the top of the machine are arranged three parallel, tubular, guide members 21, 22 and 23, the center one of which is fixed and used as a guideway for the base or block

24 of each of the slide heads 3 and 4 to insure a stable movement and proper alignment of these heads. The two guide members 21 and 23 are movable laterally in connection with the assembling and joining of the inner bars of the sash as will hereinafter be explained.

In addition to the adjustment of the slide heads by turning their screw bars, a further adjustment for the heads is provided by use of the movable adjusting plates or brackets 25. These brackets are fashioned with a pair of slotted lugs 26 for the bolts 27 of the heads 3 and 4. Each adjustable bracket has two slotted lugs 26 and two clamp bolts 27 by means of which the brackets are clamped to the slide heads for engaging against the outer edges of the top and bottom rails of the sash, and the correct gage or adjustment of the heads may thus be secured for the sash.

By reference to Fig. 9 the reciprocation of the two slide plates 5 and 6 from the power shaft 7 will be apparent. Two pairs of eccentrics as 28, 29, 28', 29' are keyed to 90 rotate with this shaft, and each eccentric has a strap as 30, 31 to which the respective screw bars 32, 33, 32', 33' are pivoted at 34. These pairs of screw bars are spaced apart as shown in Figure 1, one pair at each side 95 of the center of the machine, and are designed to form a stable, well braced actuating means for the slide plates 5 and 6, which are of greater length than the slide heads 3 and 4.

Near the outer end of each screw bar 32 33 32' 33' is carried a sprocket wheel as 35, 36, 37, 38 which wheels are connected in pairs by the sprocket chains 39 and 40 located at the outer opposite sides of the machine. Each of the sprocket wheels has a hub 41 with an interior thread for the screw bars, which hub is rotatable in a bearing ring 42 that is carried within the lower end of a supporting yoke 43. These 110 yokes 43 are provided with upper horizontal plates 44 bolted to the slide plates 5 and 6 and the plates 44 slide and are guided in grooves 45 (Fig. 9) in the table top of the machine.

A reciprocable movement is imparted to the slide plates 5 and 6 with each revolution of the power shaft 7 through the eccentric connections and the screw bars acting as pitmen.

For adjusting the slide plates 5 and 6 toward or away from the center of the machine to adapt them for use with various sizes of window sash, the sprocket chains or sprocket wheels are manipulated. The 125 hubs of the sprocket wheels then act as traveling nuts on the screw bars, and when the proper adjustment is secured the lock nuts 46 on the screw bars are turned against the inner ends of the hubs and their bear- 130

ing rings to lock the wheels on their screw bars. The chains are operated manually to turn the wheels, or one wheel of each connected pair may be turned and through its chain the complementary wheel is turned.

When the inner bars C of the window sash are being joined with the stiles and rails of the sash, the bars are supported by means of slide blocks 47 and 48 shown in Figures 10 and 11 respectively. As many of these blocks are used as are necessary and they are attached to the laterally movable guideways 21 and 23. The blocks are slidable in the guide ways to accommodate bars spaced at various distances for supporting panes of glass of differing size. The blocks 47 are fashioned with four spaced lugs 49 as guides for intersecting bars C, and an extension arm 50 of each block has spaced lugs 51 for the short bars C.

The blocks 48 each have a pair of spaced lugs 52 for the reception and support of the long bars 2 as best seen in Fig. 7. Blocks 47 are located at the center of the machine and blocks 48 are disposed at equidistant points at the right and left of the machine of Fig. 7. They are slid along in their guideways 21 and 23 to the proper position and then fixed in this position on the guideways by means of set screws 52' (Fig. 8) in the perforated lugs 59 (Figs. 10 and 11), of the blocks.

The two guideways 21 and 23 form carriers for the interior bars of the sash, and are laterally reciprocable on the frame bars 60 toward and from the fixed, center guideways 22. This movement is for the purpose of joining the inner sash bars when such sash bars are being assembled in the sash, and the movement of these carriers, which is received from the power shaft 7, is timed with relation to the movement of the heads 3 and 4 and the plates 5 and 6 in order that the inner bars are properly joined.

For actuating these carriers two cam disks as 61 and 62, (Figs. 4 and 8) are keyed to the power shaft 7 and each disk is fashioned with a depression or cam surface as 63 or 64 on its periphery. These disks co-operate with two levers as 65 and 66 joined at their free ends by spring 67 below the disks. The two levers are keyed on parallel spaced rock shafts 68 and 69 journaled in the main frame of the machine and each lever carries a roller as 70, 71 for co-action with the depression or cam face 63 or 64 of the disks. The short arms 72 and 73 (of the levers) are pivotally connected to link bolts 74, and these bolts are connected to perforated angle arms 75 fixed to the outer sides of the respective carriers 21 and 23. By means of nuts 76 on the link bolts 74 the leverage may be adjusted to vary the movement of the carriers 21 and 23.

The machine is operated by means of

power applied to pulley 75' on the drive shaft 76 which is journaled in bearings 77 at one end of the machine, and power is transmitted to the operating or power shaft 7 through a drive pinion 78 and a larger gear 79, the latter on the power shaft 7.

In connection with the drive pulley a slide clutch member 80 is used on the drive shaft, the latter being keyed to rotate with the shaft and the pulley being loose thereon. Through the engaged clutch and pulley power is transmitted to the operating shaft, and this transmission of power is controlled from a foot pedal 81 located in convenient position for the operator at the base of the machine. The pedal is suspended or pivoted in brackets 82 affixed to the horizontal bar or rod 82' of the machine frame, and at its inner end the pedal is connected by its arm 83 and pivot 83' to the bell crank clutch lever 84. This clutch lever is pivoted in the machine frame at 85, and is suitably connected with the clutch member 80 at 85' in order that the clutch member may be shifted on its shaft as the pedal is actuated. By depressing the pedal the clutch lever is actuated to shift the clutch member 80 into frictional contact or engagement with complementary clutch members 80' on the pulley for revolving the drive shaft.

A spring 83^a connecting the pedal 81 with the machine frame holds the pedal elevated, and returns the pedal to elevated position after depression. While the pedal is depressed the clutch is engaged and during engagement of the clutch device the machine is operating.

The operation of the machine is automatically stopped twice during a single revolution of the power shaft 7, which revolution causes a reciprocation of the heads and plates. During an idle period of the machine, the completed sash is removed by hand from the machine, and stiles, rails and bars for a succeeding sash are placed in position in the retracted parts of the machine for assembly and joining.

After the pedal has been depressed for the purpose of engaging the clutch to start the machine, pressure may be removed from the pedal if desired and the machine will perform its function after which its operation will be automatically stopped. This automatic operation of the machine which releases the engaged clutch mechanism including the devices 80 and 80' is accomplished through the instrumentality of a disk 86 fixed to rotate with the shaft 7, as best seen in Figure 6. The disk may be fixed in adjusted position on the shaft by means of the set screw or bolt 86', and is provided with a pair of diametrically disposed laterally projecting tappet pins 87 and 88 near its periphery.

These pins are for co-action with a pawl

89 pivoted at 90 on an arm 91 of an angular lever 92, and this angular lever is pivoted loosely to the bell crank or clutch lever 84 in such manner as to permit a slight lateral movement of the angular lever with relation to the clutch lever. The pawl is pivoted in a forked end of the arm 91 and is limited in its movement in the forked end with a counterbalanced rear end of sufficient weight to normally hold the pawl in position in full lines Fig. 6.

The arm 92 of the angular lever or release lever extends horizontally and outwardly from the machine adjacent to and parallel with the pedal 81 for ready access by the operator should it become necessary to stop the machine by an emergency release of the clutch. The angular release lever has attached to its arm 91 a spring 94, one end of which is anchored to the machine frame, for exerting its tension in pulling the release lever to the left in Figs. 3 and 6. Below the pivoted pawl on the arm 91 is a fixed laterally projecting cam-lug 95 which rides around a roller 96 journaled on a fixed bearing rod 97 of the machine frame. When pedal 81 is pressed downwardly by foot power, or in an emergency the pressure is applied to the arm 92 of the release lever to move it to dotted position, the cam-lug co-acts with the roller. Thus when the pedal is depressed to engage the clutch members 80 80' the clutch lever elevates the release lever and the cam lug rides around and above the roller 96. The spring 94 permits a slight lateral movement of the release lever 91 to allow the cam lug to ride around the roller, and then the spring pulls the arm 91 to the left in Fig. 6 to rest on top of the roller. The lug now acts as a detent on the top of the roller to hold the clutch mechanism in engaged position for operation of the machine. In this position the pivoted pawl 89 is held in the path of movement of the tappet pins on the rotating disk 86. As the machine operates the disk revolves anti-clockwise in Figure 6 and pin 88 will come in contact with the pawl. This action swings the arm 91 with its pawl on the loose pivot 93 a sufficient distance to free the detent 95 from its roller, and the pedal spring 83^a now pulls upwardly on the free end of the pedal to actuate the clutch mechanism and release or disengage the clutch members. This movement of the pedal pulls the release lever down to dotted position in Fig. 6, and as the release lever is pulled down the detent or cam lug 95 rides down and around the roller 96. The spring 94 then pulls the release lever 91 to the left in Fig. 6 drawing the detent or cam lug under the roller 96 as shown in dotted lines.

Assuming that this described movement of parts and stopping of the machine oc-

curs after the movable heads and plates have pushed the sash members inwardly on a compression stroke of the machine to join the sash members, the pedal is again depressed to engage the clutch and start the machine for a retracting movement of the heads and plates.

When inferior bars are being joined in the sash the entire sash is removed from the machine by hand at this time before the carriers 21 and 23 can move and disjoint the inner bars of the sash. After the clutch is engaged and the machine operates to retract the heads and plates, the tappet pin 87 will engage the pawl 89 to stop the machine at the end of its outward stroke with the heads, plates and carriers in position to receive elements of another sash, and the performance for operating and stopping the machine is repeated.

The push members or heads and plates are adapted to be fixed in adjusted position for various sizes and shapes of frames both as to width and height of windows and for screen door or other door frames and similar structures. For screen door frames where the door is two or three times as high as it is wide, the push-heads 3 and 4 are run out, by sliding, in the grooved rail or guide ways 22 toward the ends thereof and fixed in desired position, and the push plates 5 and 6 are provided in sufficient length to co-act with the pusher-heads in these various positions.

The machine operators stand next to the pusher plates and place the sash elements in position as well as remove the completed sash and this may be done with rapidity and convenience. The machine as thus described is capable of rapid, accurate and efficient performance of its functions in the manufacture of window, door, or other frames, and reduces the cost of labor as well as the time required for manufacture.

Having thus fully described my invention what I claim as new and desire to secure by Letters Patent is—

1. The combination with a reciprocable plate and a pair of spaced yokes thereon, of a sprocket wheel journaled in each yoke and provided with an internal thread, a sprocket chain connecting said wheels, an intermediate power shaft and eccentrics thereon, and a screw bar in each sprocket wheel having an operative connection with an eccentric.

2. In a machine as described the combination with a drive shaft and a clutch thereon and a power shaft and operative connections between said shafts, of means for actuating the clutch including a clutch lever, a disk on the power shaft having a pin thereon, a release lever pivoted on the clutch lever and a pivoted pawl on the release lever for co-action with said pin, a fixed abutment

and a detent on said release lever for co-action with said abutment.

3. The combination in a clutch actuating mechanism of a release lever having a detent thereon and a tension spring connected to the lever, a roller having a fixed journal bearing for co-operation with said detent, a

pivoted pawl on the release lever, and means for contacting with said pawl for the purpose described.

In testimony whereof I affix my signature.

OSCAR G. EDMOND.
